UNITED STATES PATENT OFFICE.

JOHN E. MORRIS, OF COLUMBUS, OHIO, ASSIGNOR OF ONE-HALF TO
EDWARD GLAZE, OF COLUMBUS, OHIO.

ELECTRICAL SWITCH.

No. 841,035.

Specification of Letters Patent.

Patented Jan. 8, 1907.

Application filed July 28, 1905. Serial No. 271,590.

To all whom it may concern:

Be it known that I, JOHN E. MORRIS, a citizen of the United States, residing at Columbus, in the county of Franklin and State of Ohio, have invented certain new and useful Improvements in Electrical Switches, of which the following is a specification.

My invention relates to a new and useful improvement in electrical switches, and more particularly to an electrical switch for illuminating purposes.

The object of the invention is to provide a switch so constructed as to prevent sticking of the contact parts, thus obviating the necessity of employing a lubricant, which is generally necessary.

Another feature lies in the arrangement of the parts, whereby all the operating parts are free from contact with the current.

20 A still further point of novelty resides in opening and closing the circuit by double contact-points operating in succession, so that sticking is obviated and flashing prevented to a certain degree.

25 Finally, the object of the invention is to provide a device of the character described that will be strong, durable, and efficient and one in which the several parts will not be liable to get out of working order.

30 With the above and other objects in view the invention consists of the novel details of construction and operation, a preferable embodiment of which is described in the specification and illustrated in the accompanying drawings, wherein—

Figure 1 is a side elevation of the switch. Fig. 2 is a plan view of the same with one of the springs broken away to illustrate the construction lying therebeneath, and Fig. 3 40 is a transverse vertical sectional view taken through one of the switch members on the line x of Fig. 1.

In the drawings the numeral 1 designates the base, of suitable non-conducting material, on which the switch parts are mounted.

It is to be understood that any number of circuits may be opened and closed by my switch, it being necessary to provide a switch member for each circuit, and as these switch members and their parts are of substantially the same construction a description of one will suffice for the rest.

Mounted on the base and spaced apart are suitable contact-plates 2 and 2^a, which are

held in position and connected with binding-screws 3 and 3^a. Either of the binding-screws 3 may be connected with the feed-wires (not shown) leading from the source of electrical supply, while one of the binding screws or posts 3^a is connected, by means of a suitable contacting plate 4 on the under side of the base, to a terminal 5 of a suitable fuse socket and plug 6, from which the current is suitably transmitted to the lamps.

The circuit is closed or the contact-plates 2 and 2^a connected by a movable bridge-contact 7, composed, preferably, of a number of copper strips bearing at each end on the plates. The bridge-contact is supported at the lower end of a hanger 8 on a washer 9, of suitable non-conducting material, through which is passed a screw 10, driven into place in the hanger. The screw passes through the copper strips, but is insulated therefrom by a bushing 11, which also passes through a spring-bow 12, arranged over the bridge and insulated from the hanger by a strip of non-conducting material 13. The screw 10 thus serves to hold the parts closely together and securely in position on the lower end of the hanger. The spring-bow 12 has its opposite ends turned under, as clearly illustrated in Fig. 1. On the undeturned ends of the spring-bow carbon contact-blocks 14 are securely fastened by bolts 15. These carbon blocks contact with the plates 2 and 2^a, the current thus not only passing from one plate to the other through the bridge 7, but also through the spring-bow 12. The elasticity of the bow tends to hold the blocks 14 in contact with the plates 2 and 2^a, thus allowing the bridge 7 to be raised off of the contact-plates a short distance before the said blocks are raised.

In this manner when it is desired to open the circuit and the bridge is raised out of contact with the plates there is no tendency on the part of the contact parts to stick, as the circuit is still closed through the carbon blocks 14 and the spring-bow 12, and when the hanger 8 is raised high enough to pull the blocks off the contact-plates, completing the opening of the circuit, there of course will be no sticking on account of the nature of the blocks and also the flashing or sparking will be reduced to a minimum. It is to be observed that both the bridge 7 and the spring-bow 12 are thoroughly insulated from the hanger 8, thus preventing the cur-

rent from passing over the same or any of the other parts which are about to be described.

For raising and lowering the hanger 8 to open and close the circuit I pivotally support the same at the extreme ends of levers 16 and 17, pivotally connected to a bifurcated post 18, the lever 16 being connected to the upper ends of the hanger and the post, while the lever 17 is arranged some distance below. Coiled springs 19 are connected with the lever 17 and the upper end of the post 18 and tensioned so as to swing the levers upward. On the lever 16, near the post 18, a curved arm 20 is adjustably mounted, having a bifurcated end and carrying a roller 21, preferably formed of a suitable non-conducting material. This roller projects into the path of segmental cam-pieces 22, arranged on the outer periphery of a drum 23. It is to be understood that the drum 23 may be of any width, according to the number of circuits and switch members employed. In the drawings I have shown four switch members. Consequently four rollers 21 are provided, each 25 roller projecting into the path of two cams arranged on the drums. The cams may be arranged as desired and at different points, so as to open and close different circuits at different predetermined times or points. 30 The cams are provided with rounded and reduced ends, so that the rollers will readily ride thereon and roll off thereof sharply. When one of the cams passes under the roller, it will of course be forced away from the 35 drum, and being secured to the lever 16 will force the same downward, thus moving the lever 17 and the hanger 8 downward against the tension of the springs 19. The blocks 14, hanging lower than the bridge 7, will first engage with the metallic contact-plates 2 and 2^a, thus closing the circuit, and as the cam continues to force the roller away from the drum the bridge 7 will be brought into contact with the plates and the circuit thus 45 finally closed, the parts remaining in these positions as the cam continues to pass under the roller until its end finally passes from the roller, when the same will drop or be forced against the periphery of the drum by the action of the springs 19, which at the same time swings the levers and the hanger 8 upward. This upward movement of the hanger of course first raises the bridge 7 off the contact- 50 plates, then raises the blocks out of contact with said plates, thus opening or breaking the circuit, which condition exists until the second cam encounters the roller, when the closing operation is completed. It will be apparent that owing to the high resistance 55 of the carbon blocks the contact-bridge of low resistance is necessary and produces a more positive conductor when brought into contact with the plates, although the blocks will close the circuit without any detrimental effects.

It will be apparent that the rapidity with which the drum is revolved will govern the opening and closing of the various circuits and that the drum may be revolved by any suitable means, and I have shown in the drawings one manner of imparting motion thereto. The drum 23, as shown, consists of a cylinder braced at each end by spiders 24, through which projects a shaft 25. The shaft 25 is supported in the bearing-boxes 26 of suitable standards 27, mounted on the base 1. A yoke-hanger 28 is engaged about one of the bearing-boxes and supports a worm-screw 29, which may be driven by any suitable means, such as a pulley 30. The worm-screw meshes with a worm-gear 31, fixed on the shaft 25. The power thus transmitted to the pulley 30 will revolve the worm-screw 29, which in turn will revolve the worm-wheel 31, thus imparting motion to the drum 23, and the speed of the drum can of course be regulated by the speed of the worm screw and gear. By arranging the hanger 28 on the bearing-box it is apparent that the same may be swung on the bearing-box so as to cause the worm-screw 29 to stand at different angles to the base 1, it being shown in the drawings as lying parallel to the base; but it is apparent that by swinging the hanger on the bearing-box the worm-screw may be caused to project at right angles to the base and that suitable means may be provided for locking the hanger in position on the said bearing-box.

Having now fully described my invention, what I claim, and desire to secure by Letters Patent, is—

1. In a device of the character described, the combination with a base, of a fixed support mounted upon said base, a pair of parallel arms pivoted to said fixed support, a hanger to which the free ends of said parallel arms are pivoted, a spring adapted to lift said arms and said hanger, a pair of separated contact-plates mounted upon the base, a connecting member carried by the hanger and adapted to connect said plates when said hanger is at its lowest limit of movement, a rotative member, cams carried by said rotative member, an arm carried by one of the pivoted parallel arms, and an antifriction-roller carried by said arm and adapted to be engaged by said cams.

2. In a device of the character described, the combination with a base, a fixed support, a pair of parallel arms pivoted to said fixed support, a hanger to which the free ends of said arms are pivotally connected, a spring one end of which is connected to said support and the other end of which is connected to one of the parallel arms, means for intermittently forcing said arms downwardly against the tension of said spring, separated contact-plates, a plurality of contact members carried by the hanger and adapted to

- connect said contact-plates when the hanger is at its lowest limit of movement, a member carried by one of the parallel pivoted arms, and a roller carried by said member.
- 5 3. In a device of the character described, the combination with a base, of a fixed support, a pair of parallel arms pivoted to said fixed support, a hanger to which the free ends of said arms are pivoted, contact-plates, a plurality of contact members carried by the hanger and adapted to connect said contact-plates when the hanger is at its lowest limit of movement, means for lifting said hanger and said contact members from the contact-plates, a roller supported from one of the pivoted parallel arms, and members adapted to intermittently engage said roller to force the hanger downward.
4. In a device of the character described, the combination with a fixed support, of a pair of parallel arms pivoted to said fixed support, a hanger to which the free ends of said arms are pivoted, a pair of separated contact-plates, a contact member carried by said hanger and adapted to connect said contact-plates, a resilient member for withdrawing said contact member from said contact-plates, a member connected to one of the pivoted parallel arms, a rotative member, and members carried by said rotative member and adapted to engage the member carried by the pivoted parallel arm to force said arms downwardly or against the tension of the resilient member.
- In testimony whereof I affix my signature in presence of two witnesses.
